UNITED STATES PATENT OFFICE.

HARRY CHESSLER, OF BROOKLYN, NEW YORK.

CONVERTIBLE COUCH BED.

Application filed January 24, 1924. Serial No. 688,269.

To all whom it may concern:

Be it known that I, HARRY CHESSLER, a citizen of the United States, residing at Brooklyn, in the county of Kings and State of New York, have invented certain new and useful Improvements in Convertible Couch Beds, of which the following is a specification.

The present invention relates to couch beds, particularly of the type in which the couch bed is composed of two superposed sections, which can be extended or contracted to form respectively a bed or couch.

In the accompanying drawing in which similar reference characters denote corresponding parts, Fig. 1 is a top plan view of the extended couch bed; Fig. 2 a cross section on line 2—2 of Fig. 1; Fig. 3 a cross section on line 3—3 of Fig. 2, and Fig. 4 a sectional view of a part of the collapsible section of the couch bed somewhat enlarged.

The convertible couch bed, according to this invention, is composed of two vertically superposed sections 10 and 11 of which section 10 constitutes the main or stationary frame and section 11 the collapsible section, which, when extended and unfolded, forms with the main frame a double bed.

12 denotes the supporting ledge for the spring mattress 13 or the like of the main frame and 14 denote the feet of the latter. The foldable or collapsible section 11 is adapted in contracted position to occupy the space 15 below the spring mattress 13 of the main frame. To this end below the ledge 12 and somewhat above the feet of the main frame a pair of horizontally disposed angle irons 16 or the like are fixed to the main frame one at each end of the latter. These angle irons constitute supports on which slidably bears the collapsible section 11. The latter is composed of two vertically superposed rectangular frames 17 and 18 of which the lower one 17 is formed

45 at its end portions with casters 19 adapted to bear on the floor. These frames extend throughout the entire length of the main frame and serve, when unfolded and retracted from the latter, to support a spring mattress 20 which together with the collapsed section is adapted to be accommodated in the space 15. The lower frame 17 at its front has fixed to it a vertical board or panel 21, which in the contracted condition of the couch bed, is adapted to serve as a wall for the front opening of the space 15 and is

made substantially of a length equal to that of the main frame. For the purpose of symmetry, the space 15 may be closed at its rear by a stationary board or panel 22. The rear part of the lower frame 17 is adapted to slidably bear on the angle irons or ledges 16 and is formed with a downwardly extending projection 23, which when the collapsible frame is retracted from the main frame will abut against a block or bar 24 or the like and serve as a stop, preventing the complete withdrawal of the collapsible section from the space 15. The upper frame 18 is somewhat smaller in its dimensions than the lower frame 17 and is capable of being collapsed, so as to fit in the main frame 17 and occupy with it the same plane. To this end, it is movably supported by two pairs of arms 25 pivoted thereto at 26 and 75 fulcrumed at 27 to the lower frame 17, the arms being in length so admeasured that when the frame 18 is raised, it is even with the ledge 12. By virtue of these swinging arms, the upper frame 18 will be capable of moving parallel to itself and relative to the lower frame 17. Movably supported about centrally on the front part of the upper frame 18 is a U-shaped handle 28 the legs 29 of which are formed with longitudinal recesses 30 slidably engaging screw bolts 31 or the like fixed to the frame 18. Fixed to the inner face of the board or panel 21 and about centrally thereof is a recessed or looped horizontally disposed bar 32 so arranged that the loops or recesses 32' thereof register with the legs 29 of the handle 28 and are capable of engaging said legs, whereby the upper frame 18, when in raised position, may be locked to the lower frame 17. The panel 21 at its upper edge just above the bar 32 is cut away, as at 21', so as to enable the grasping of it by the hand, when the couch bed is contracted.

The manipulation is as follows:

When the couch bed is contracted and converted into a couch, the collapsible section 18 occupies the space 15, the latter being closed by the front panel 21. When it is desired to unfold or extend the couch bed, the panel 21 is grasped at the recessed portion 21' and pulled forward, thereby withdrawing the foldable section 11 from the space 15, until the nose 23 strikes the block 24. In this position, the panel 21 occupies the dotted line position shown in Fig. 2 and the frames 17, 18 are collapsed

as indicated by dotted lines in Fig. 2 or in full lines in Fig. 4. Now on grasping the handle 28 and pulling it upwardly, the latter will be raised, until the screws 31 bear 5 against the lower ends of the slots 30 and the frame 18 swung into its raised position. Thereupon and while still holding the handle 28 with one hand, the panel is moved back until the upper frame 18 strikes the 10 ledge 12. In this position, the looped bar 32 will register with the legs of the handle, so that on releasing the latter, it will by its own gravity fall into locking position and lock the collapsed frame in the raised position. 15 The folding or contracting of the couch bed is effected by first raising the handle 28 and thereby unlocking the frames 17, 18, then moving the panel into the dotted line position (Fig. 2) and permitting the frame 20 18 to swing into the plane of the frame 17 and pushing the collapsed section into the space 15. The collapsible frame 18 may be suitably counterbalanced, so as to be movable with the least possible effort and the frame 25 17 may be provided with ball bearings (not shown) to facilitate its sliding movement on the ledges 16.

It is clear that the above described structure is very advantageous in that the folding 30 and unfolding of the couch bed can be performed very quickly and easily and without disarranging the pillows on the couch or main section 10.

What I claim is:—

35 1. A convertible couch bed structure comprising a stationary section having at its bottom a free space, a collapsible section

adapted to be accommodated in said free space and composed of two vertically superposed frames connected by swinging arms, 40 so that the upper one is capable of moving parallel to itself and relative to the lower frame, means in the stationary section on which said lower frame may be slidably extended outwardly, a movable grasp on said 45 upper frame and means on said lower frame to engage said grasp to lock said upper frame in raised position, when said collapsible section is extended.

2. A convertible couch bed structure comprising a stationary section having at its bottom a free space, a collapsible section adapted to be accommodated in said free space and composed of two vertically superposed interconnected frames of which the upper one is movable relative to the lower one and parallel to itself and capable in collapsed position of occupying the same plane as the lower one of said frames, means on said stationary section on which said lower 60 frame may be slidably extended outwardly, a movable grasp on said collapsible section and locking means of which said grasp forms a part and whereby the upper one of said frames is locked in raised position, 65 when said collapsible section is unfolded or extended.

In testimony whereof I affix my signature in presence of two witnesses.

HARRY CHESSLER.
